UNITED STATES PATENT OFFICE

2,062,730

AUXILIARY GRINDER FOR MILLS

George Schilling, Cleveland, Ohio

Application April 28, 1936, Serial No. 76,799

1 Claim. (Cl. 83—22)

This invention relates to auxiliary stationary grinders attachable to mills having a horizontal cylindrical grinding member and relates particularly to mills adaptable for grinding paints, 5 pigments, or other viscous materials.

A conventional paint mill of the type referred to consists of three rollers, two of which co-act as crushers and the third reciprocating roller serving as a grinding member. In such mills 10 the material to be ground is fed to the crushing rollers at the top, carried through the nip around to the third roller where it is further ground and then removed for further processing.

An object of my invention is to provide a mill 15 of the type referred to with an auxiliary grinding member that is simple of construction, economical to manufacture, and with one which is easy to regulate, clean and adjust.

Another object of my invention is to provide 20 an auxiliary stationary grinder that will supplement or increase the efficiency of the grinding action of the grinding roller.

A further object of my invention is to provide 25 an auxiliary grinder with a simple and efficient cooling means.

A still further object of my invention is to provide 30 an auxiliary fixed grinder with supporting arms which automatically positions the grinder in relation to the reciprocating rotary grinder.

These and other features of my invention are 35 more fully set forth hereinafter; reference being made to the accompanying drawings, in which:

Figure 1 is a side view of a mill with the auxiliary grinder attached thereto.

Figure 2 is an enlarged front view of the auxiliary grinder.

Figure 3 is a side view of the auxiliary grinder enlarged.

Figure 4 is a sectional view of the arm and 40 block assembly taken along the lines IV—IV of Figure 3.

Figure 5 is a vertical cross-sectional view of 45 the auxiliary grinding block taken along the lines V—V of Figure 2.

Figure 6 is a horizontal cross-sectional view 50 of the auxiliary grinding block taken along the lines VI—VI of Figure 5.

In Figure 1 of the drawings I show a mill of 55 the type to which my invention can be easily attached. This mill is of the horizontal roller type and has a base 11, in which is mounted three steel cylindrical rollers 12, 13, and 14, respectively. The rollers 12 and 13, revolve in-

wardly at the top and act as crushers of the 5 material fed to them. The right-hand roller 14, co-acting with the middle roller 13, serves as a grinder. The middle roller 13, is usually stationary, but the end rollers 12 and 14, are moveable outwardly by means of the screws 15, to facilitate cleaning, adjusting or repairing. The 10 tension or pressure of the rollers is controlled by the springs 16, between them. Because of the heat that is generated by friction in the crushing and grinding process the rollers have 15 cooling means within them, and in the Figure 1, I show water pipes 17, leading to the rollers for this purpose. The character 18, indicates a scraper used to remove the material from the 20 roller 14.

With reference to the foregoing my invention 25 consists of a grinding block 20, which fits over the roller 14, the brackets 21, mounted on the base or supporting frame 11, and the arms 23, pivoted to the said brackets and the said 30 block.

The grinding block 20, is preferably made of 35 a natural stone, but a very satisfactory block can be made artificially of cement and crushed granite. The bottom surface of the block 20, 40 is concave so as to fit neatly over the top of the roller 14. The rear lower edge 24, of the block is slightly flared in order to allow the mixture to reach the grinding surface without the nip at 45 that point acting as a scraper.

I provide the block 20, with upright posts 25, over which removable weights 19, can be placed. The posts 25, are set near the sides of the block 20, and by either increasing or decreasing the 50 weights placed thereon, the texture of the finished product is easily controlled, and the natural wear of both the roller 14, and the block 20, is evenly distributed. I further provide the block 20, with handles 26, to enable the operator to raise or lower the said block when it becomes 55 necessary to do so for cleaning.

Through the approximate center of the block 20, I imbed or affix a shaft 27. This shaft preferably a steel rod, is made parallel to the concave surface of the block 20, and extends outwardly from its sides for a short distance. Four 60 removable collars 33, are affixed to the shaft by set screws 34. Two collars are placed on each end of the shaft and one on each side of an arm 65 23.

I also imbed in the block 20, water pipes 28, to 70 which are attached an inlet hose 29, and an outlet hose 30, for cooling the grinding surface of the block 20. The water lines can be easily connected 75 to the main water pipes 17, of the mill.

- The arms 23, have an adjustable coupling at their ends for engaging the shafts 27, of the block 20. The arms 23, have longitudinal slots 31, horizontally through their sides and adjusting screws 32, through their ends and entering into the slots 31. Within each of the slots 31, I insert a compression spring 35, a lug 36, and a slidable cap 37, which engages the end of the adjusting screws 32, and an end of a compression spring 35. The lug 36, has a concave end surface, fits the periphery of the shaft 27, and slides within the slot 31, between the collars 33. The cap 37, is held within the slot 31 by the side guides 38. This adjustable coupling I find necessary not only for simplifying the removal of the block 20, from the rest of the apparatus, but also for insuring an even and uniform grinding surface at all times regardless of the lateral movement of the rollers 14.
- For the purpose of retaining the arms 23, and the block 20, in a raised position I equip the brackets 21, and the arms 23, with folding brackets 39, which in themselves are well known. The Figure 3, shows the position of the arm 23a, and the folding brackets 39a, in the raised or alternate position.
- With the construction I have described it is possible to clean, remove, or repair the grinding block 20, with very little trouble. All that is necessary to remove the block 20, from the rest of the apparatus is, first, to remove whatever weights 19, may be thereon; second, loosen the set screws 34, and the collars 33, so that the spring 35, and the lug 36, will come out of the slot 31. The block 20, and the shafts 27, can then be moved and shifted sidewise and upward until the shafts are out of their respective slots.

With my auxiliary grinder, by increasing the

actual grinding surface of the roller 14, and by supplementing the effectiveness of the grinding nip between the rollers 13 and 14, I correspondingly increase the efficiency of the mill, and I also eliminate necessity of having to re-grind the material in the same or in other machines in order to obtain a finished product.

It is quite obvious also that a second auxiliary grinder of the same type as I have described can be installed over the left roller 12, thereby further increasing the efficiency of the mill unit.

Having described my invention in its simplest form, and having used special words and terms in the description, I reserve the right to make such changes in form, construction and proportions of parts that may be made without departing from the essence of the invention or the scope of the following claim.

I claim as my invention:

In a mill of the class described, an auxiliary grinder, comprising in combination, a supporting frame, a rectilinear grinding block having a longitudinal concave grinding surface the nip of which is flared, the said block having a shaft extending therethrough and projecting outwardly from its sides parallel to the concave grinding surface, water pipes for cooling the said block imbedded therein, posts mounted on the top of the said block for retaining weights thereon, brackets mounted on the said frame, arms attached to the ends of the said shaft and pivotally connected to the said brackets, holders pivoted to the said arm for supporting the said block in a raised position, and handles attached to the said block for raising the same.

GEORGE SCHILLING.
